UNITED STATES PATENT OFFICE.

WALTER RATLEDGE TWIGG, OF LUTON, ENGLAND.

GAS-FIRED FURNACE.

Application filed March 29, 1918. Serial No. 225,501.

To all whom it may concern:

Be it known that I, WALTER RATLEDGE TWIGG, a subject of His Majesty the King of England, and resident of Luton, in the county of Bedford, Kingdom of England, have invented certain new and useful Improvements Relating to Gas-Fired Furnaces, of which the following is a specification.

10 This invention relates to reversible regenerative gas fired furnaces, and has for its object to provide an improved construction of furnace which is especially adapted for, although not limited to, use with coal-gas and air under pressure. The term coal-gas is intended to denote gas obtained from the distillation of coal, with or without admixture of water gas and coke oven gas, which gas requires at least three volumes 15 of air for its complete combustion, such as supplied by the statutory coal gas companies. It has heretofore been proposed to use a reversible regenerative furnace operating on coal gas, the regenerative chambers in such furnace being situated entirely outside the furnace structure and containing fragmentary material packed to such extent in the regenerative chambers as to necessitate forcing the air required for combustion 20 through the said packed material in the regenerative chambers under pressure.

The use of regenerator chambers formed entirely within the furnace structure is known and also the simultaneous reversal 25 of the flow of gas and pressure air to the furnace.

According to the present invention, the furnace comprises in combination, a furnace chamber; pressure air regenerator chambers formed entirely within the furnace structure, means to deliver pressure air to the regenerator chambers, means to deliver coal gas to the furnace chamber and means to reverse the direction of the 30 flow of the gas and pressure air to the furnace simultaneously.

The gas and pressure air are admitted to each side of the furnace alternately, each conduit or pipe through which the air for combustion with the gas is delivered to the furnace acting alternately as an air supply passage common to all of the gas inlets then in action, and on reversing as a flue for the escape of the exhaust products of combustion to the chimney or furnace flue. Underneath the furnace hearth is a chamber,

which is divided into two parts by a partition arranged at right angles to the gas inlets to the furnace and preferably centrally thereof, each part forming a regenerative chamber for secondary air to the furnace. A gas supply pipe is arranged externally and on each side of the furnace, each of which gas pipes delivers gas to a plurality of gas inlets in each side of the 45 furnace.

The air supply pipes are arranged outside and one on each side of the furnace, each pipe supplying air to a plurality of air inlets. Each regenerative chamber is 50 subdivided into two or more regenerator chambers, each pair of such chambers having a common pressure air inlet subsequently branched and leading to or connecting with the said two chambers, which 55 are capable of supplying a suitable volume of pressure air for combustion with the gaseous fuel issuing from one or a plurality of gas inlets.

Manually operated means are also provided to simultaneously actuate the air controlling valve and the gas controlling valves so as to divert the flow of gas and pressure air to the separate gas and pressure air inlets on either side of the furnace as desired, 60 and to allow the escape of the exhaust products of combustion through the air pipe or pipes then inoperative as air supply pipes to the furnace.

I will describe with reference to the accompanying drawings, constructions in accordance with the present invention as applied to different types of gas fired furnaces, but I neither limit myself to the precise constructions described and illustrated nor 75 to the types of furnaces to which the invention may be applied.

Figure 1 is a diagrammatic sectional elevation of a furnace in accordance with the present invention.

Figure 2 is a side elevation of a multiple type of furnace in accordance with the present invention.

Figure 3 is a sectional plan on the line 3-3, Figure 5.

Figure 4 is a longitudinal section on the line 4-4, Figure 3.

Figure 5 is a cross section on the line 5-5, Figure 3.

Figures 6 and 7 are respectively a longitudinal section and a cross section of a reverberatory tank type of furnace showing

the invention applied thereto. The same reference numerals wherever repeated throughout the drawings indicate the same parts.

5 Referring to Figure 1 of the drawings, 1 indicates the hearth, 2 the combustion chamber, 3 the enclosing structure, 4 the pressure air inlet on the left hand side of the furnace, and 5 the pressure air inlet on the right hand side of the furnace. The gas or coal gas, as hereinbefore defined, is admitted to the left hand side of the furnace by the inlet opening 6, and to the right hand side of the furnace by opening 7. The pressure air preheating or regenerating chambers are indicated at 8, 9. 10 is the pressure air supply pipe leading to a controlling valve 11, branches 12, 13 being led therefrom to the pressure air preheating or regenerative chambers 8, 9. These latter chambers are connected by openings 4, 5 to each side of the furnace. The gas supply pipe is indicated at 16, suitable branch pipes 17, 18 being led therefrom to the left and right-hand sides of the furnace as shewn. Suitable gas controlling valves 19, 20 are inserted in the branched gas pipes 17, 18, the spindles of the said gas controlling valves being connected by levers 21, 22 to a common rod 23, which is also connected by a lever arm 24 to the valve spindle of the pressure air controlling valve 11, and simultaneously operated therewith. In the present example the valve is shewn as a diametric vane 11. The levers 21, 22, 24 are so arranged and connected to the rod 23 having a manipulating handle 25, that pressure air is admitted to say the left hand side of the furnace, through the preheater or regenerator 8 and opening 4, and gas is admitted through the pipe 17, the admission of pressure air and gas to the right hand side of the furnace being completely shut off during this time. The exhaust products of combustion, pass 45 through the opening 5, preheating or regenerating chamber 9, pipe 13 to the valve 11 and from thence to the furnace chimney or flue. After the furnace has run for such time as may be found consistent with maximum efficiency, as indicated by the temperature of the exhaust products of combustion passing through the pressure air pipe acting at the particular time as an exhaust passage, the admission of pressure air and gas to the left hand side of the furnace is shut off and gas is then admitted through the valve 20 and pipe 18, and pressure air is simultaneously admitted to the right hand side of the furnace through the pressure air controlling valve 11, pipe 13, preheater or regenerator 9, and opening 5, to the furnace. The operation is thus cyclic and may be continued as long as desired. It may here be pointed out that the pressure air in all cases must pass through a preheater or re-

generator before reaching the furnace, and that each preheating or regenerating chamber 8, 9 alternately acts as a preheating chamber and as a chamber which absorbs the heat from the exhaust products of combustion passing therethrough.

Figures 2, 3, 4 and 5 show the invention applied to a sectional gas-fired furnace. In this construction, the furnace as a whole comprises a brickwork structure 3 corresponding to that of Figure 1 and preferably rectangular in cross section. The furnace structure may be of any other suitable and convenient section. In the interior the furnace is provided with a hearth 1, below which are arranged a plurality of chambers 8, 9 on each side of the furnace. The chambers are provided with loose fire bricks, or chequered brickwork, so as to form zig-zag passages 26 through a built up or other suitable brickwork structure. A brickwork partition 27 is provided between each of the chambers 8, and a similar partition 28 between the chambers 9, there being a central partition 29 between the two sets of chambers. A gas inlet 30 is arranged at or near the upper level of the hearth 1, the said inlet being preferably formed by a tube 31 let into the structure 3 and discharging into a suitably shaped space 32 provided in the brickwork structure 3 adjacent the hearth 1. The aforesaid space 32 forms a recess, through which the whole or part of the pressure air for combustion from one regenerator or preheater chamber 8 passes on its way through the opening 33 to the combustion chamber 2. A similar gas inlet 34, and also an inlet 35 for the whole or part of the pressure air for combustion, are arranged in the opposite side of the furnace. The furnace is thus provided with a plurality of gas inlets 30 on one side, and a plurality of gas inlets 34 on the opposite side of the furnace, co-operating pressure air inlets 33 and 35 being provided adjacent the respective gas inlets.

Preferably arranged along each side and outside of the furnace are two tubes or pipes 36, 37 on one side; and 38, 39 on the other side of the furnace, 36 and 38 being the upper pipes on each side and 37, 39 the lower pipes. These pipes extend beyond the rear of the furnace as shewn more particularly in Figures 2 and 3. The pipes 36 and 38 are connected to the gas main 40 and the pipes 37, 39 to the main air supply pipe 41. In the construction shown, the lower pipes 37, 39 are connected by a common cross pipe 42 provided with a valve, hereinbefore referred to as 11, for controlling the supply of the whole or part of the pressure air for combustion, and the escape of the exhaust or waste gases from the furnace which gases pass through one or other of the lower pipes 37, 39 to the chimney or flue 59.

Secured at intervals to, and along the length of each pipe 36 and 38 are a number of gas burners 47 of the Bunsen or other suitable type, the nozzle 48 of each 5 burner being arranged below, and if desired projecting into, the flared end of a tube 49 leading to the gas inlet tube 31, let into and suitably supported in the wall of the furnace structure, the continuity of the 10 connections for the gas supply from the pipes 36, 38 to the burners being thus interrupted or broken. The several burners 47 on each side of the furnace are preferably provided with valves 50 arranged between 15 the branched gas supply pipes 36, 38 (not the main gas supply pipe), and the nozzle 48 from which the gas issues into the flared tube 49, into which air may be induced by the gas issuing from the burner 20 nozzles 48.

The lower pipes 37, 39 may be arranged at any convenient level, and from these pipes which are plugged or closed at their front ends, branch pipes 51, 52 are led to 25 the several preheating or regenerating chambers below the furnace hearth. The inlet passages 53 for pressure air to each of the preheating or regenerating chambers 8, 9 may if so desired be forked or 30 branched as shewn at 54, 55, Figure 3, after passing through the furnace wall 3, the two passages being separated by a partition 56 of brickwork having if desired, suitable openings therein and arranged at intervals 35 in the height of the partition.

In the construction shewn in Figures 2, 3, 4 and 5, a plurality of preheating or regenerating chambers are preferably employed, these chambers being situated below 40 the hearth 1 and arranged in sets of four, two sets of two separate or communicating chambers 8, 9 on each side of the partition 29 arranged centrally, and extending longitudinally of the furnace. There are thus 45 two preheating chambers on each side of the central partition 29, each chamber having a separate pressure air inlet, which is subsequently branched as already stated to admit through passages 54 and 55 the necessary 50 volume of pressure air for combustion. Each chamber 8 and 9 has thus two inlets 55 supplying sufficient air for four gas inlets 30.

The stem or spindle 57 of the pressure 55 air controlling valve 11 is connected by a lever arm 24 to a rod 23, which is connected to gas controlling valves 19 and 20 by means of the lever arms 21, 22. As in the construction shewn in Figure 1, the gas 60 controlling valves are arranged one in each branched gas supply pipe 36 and 38 leading from the gas main 40, and between the last burners of the gas burners 47 on each of the upper pipes 36, 38 and the gas supply 65 main.

The three valves, viz, the pressure air controlling valve 11, and the gas controlling valves 19 and 20 can thus be simultaneously controlled so as to direct the pressure air and gas to say the left hand sections of 70 the furnace for any desired length of the time, whilst closing the admission of pressure air and gas to the right hand sections of the furnace. During this period, the exhaust products of combustion or the waste 75 gases escape through the pressure air inlet openings 35 on the right hand side of the furnace, and from thence by the preheater or regenerator chambers 9, pipe 39, pipe 42, valve 11 and pipe 58, to the chimney or flue 59. The relative positions of the three valves 11, 19 and 20 are then altered by operating the rod 23 so as to close the admission of gas and pressure air to the left hand section of the furnace, whilst at the same 80 time admitting pressure air and gas to the right hand section of the furnace. The exhaust products of combustion, or the waste gases resulting from the combustion of the gas and pressure air admitted to the right 85 hand section of the furnace escape through the pressure air inlets or openings 33, the preheater or regenerator chambers 8, pipe 37, pipe 42, valve 11 and pipe 58 to the furnace chimney or flue 59. The side at which 90 combustion takes place is then reversed or changed to the left hand side of the furnace, and the reversible action is continued as long as desired, using producer gas, or coal 95 gas as hereinbefore defined, or other suitable permanent gas as a fuel, and pressure air for combustion.

In the construction shown in Figures 6 and 7, the hearth is indicated by the reference numeral 1, and the combustion chamber by 2. The furnace walls are indicated generally by the reference 3. The preheating or regenerating chambers are shewn at 8 and 9 and the pressure air valve at 11. The gas controlling valve shown at 69 is 110 somewhat similar to the pressure air controlling valve 11, in that the said valve is adapted to control both gas inlets to the furnace, the diametrically arranged vanes 70, 71 of the pressure air valve and the gas 115 controlling valve respectively being reversely disposed as shewn. 72 is the pressure air supply pipe, and 73 the gas supply pipe. The pressure air controlling valve casing is provided with oppositely disposed 120 outlets leading by the pipes 74 and 75 to opposite sides of the furnace and opening into the combustion chamber 2 above the gas inlets 76, 77, to which gas is supplied from the main 73, through the valve casing 69 125 and pipes 78, 79.

The method of operating this type of furnace is the same as described with reference to the other figures of the drawings. The furnace is started up in any suitable man- 130

ner, and pressure air and gas are admitted by the openings 80 and 76 respectively, the furnace being allowed to run as long as desired while the pressure of air and gas enter 5 from these two openings. The products of combustion or the waste gases pass by the openings 81 preheating or regenerating chamber 9, pipe 75, valve casing 11 and pipe 82 to the furnace flue. The positions of the 10 diametrical vanes 70, 71 are then altered so as to close the admission of pressure air and gas through the inlets 80 and 76. The gas pressure and air is thus diverted so as to flow through the inlets 77 and 81 at the 15 right hand side of the furnace, the products of combustion or waste gases passing by the opening 80 preheating or regenerating chamber 8 pipe 74, valve 11 and pipe 82 to the furnace flue or chimney. The preheating or 20 regenerating chambers 8, 9 thus respectively act simultaneously, one, 8 to heat the incoming pressure air to the furnace, and the other, 9, to absorb heat from the products of combustion or waste gases passing 25 through the said chamber 9. On reversal, the chamber 9 heats the incoming pressure air and the chamber 8 absorbs the heat from the products of combustion or waste gases passing therethrough.

30 If desired by-pass connections 83, Figure 2 may be provided between the main air supply pipe and the gas branch supply pipes, suitable valves 84 being provided for controlling the admission of by-pass air to the gas supply pipes which by-pass air may 35 form the primary air for combustion. Such by-pass connections may be arranged to deliver primary air in parallel as at 83, or separately as at 85 to each individual burner.

40 The air-by-pass valves, main air controlling valve and gas valves may be simultaneously controlled.

The brickwork structure forming the sectional furnace hereinbefore described may 45 be strengthened by H beams and channel beams and tie rods or other members of suitable section.

What I claim is:—

1. A reversible regenerative furnace comprising a furnace structure having a hearth, 50 pressure air regenerator chambers provided underneath the said hearth and within the furnace structure, means to deliver pressure air to the regenerator chambers, means to deliver coal gas to the furnace combustion chamber, openings in the furnace hearth adjacent the outlet end of the gas delivering means to permit admixture of air and gas for combustion, and means to effect 55 reversal of the direction of the flow of the gas and air.

2. A reversible regenerative gas fired furnace, comprising, in combination, a combustion chamber, pressure air regenerator chambers 60 entirely within the furnace structure,

a supply pipe for gas on each side of the furnace and exterior thereof, a pressure air supply pipe on each side of the furnace and exterior thereof, a plurality of separate gas inlet passages leading from each gas pipe to the adjacent part of the combustion chamber, a plurality of separate pressure air inlet passages leading from each pressure air pipe to the adjacent regenerator chamber, means to reverse the direction of flow of the 70 gas and air from one side of the furnace chamber to the opposite side, each air inlet pipe acting alternately as an air supply passage common to all the gas inlets then in action, and upon reversing the flow of the 75 gas and air acting as a flue or passage for the escape of the exhaust products of combustion to the chimney or furnace flue.

3. A reversible regenerative gas fired furnace, comprising, in combination, a combustion chamber, a chamber underneath the hearth divided into two parts by a partition, each part communicating by an opening with the combustion chamber and each part of said chamber forming a regenerator chamber for secondary air to the furnace, gas inlets leading into the combustion chamber at each side above said openings, a gas supply pipe arranged externally of said furnace and feeding said gas inlets, air supply pipes arranged exteriorly of said furnace and connecting with the bottom of each part of said chamber, each air supply pipe acting alternately as a pipe for supplying air 90 only and as an exhaust pipe for the escape 95 of the exhaust products of combustion to the chimney flue.

4. A reversible regenerative gas fired furnace comprising a furnace structure having a hearth and a combustion chamber, pressure air regenerator chambers provided underneath said hearth and within the furnace structure, each regenerator chamber being divided by a transverse partition to form two separate regenerator chambers, 100 means to deliver pressure air to the regenerator chambers, means to deliver coal gas to the furnace combustion chamber, openings in the furnace hearth to permit admixture of air and gas for combustion, and means to effect reversal of the direction of 105 the flow of the gas and air.

5. A reversible regenerative gas fired furnace, comprising, in combination, a combustion chamber, a chamber underneath the furnace hearth divided by a partition into two parts, each part being sub-divided into two or more regenerator chambers, gas inlets leading into the combustion chamber at each side, a gas supply pipe arranged externally of said furnace and feeding said gas inlets, air supply pipes arranged exteriorly of said furnace, each pair of such chambers having a common pressure air inlet capable of supplying a suitable volume of 110 115 120 125 130

pressure air for combustion with the gaseous fuel issuing from two gas inlets.

6. A reversible regenerative gas fired furnace comprising in combination a combustion chamber, pressure air regenerator chambers inside the furnace structure, a gas supply pipe on each side of the furnace and exterior thereof, a pressure air supply pipe on each side of the furnace and exterior thereof, a plurality of separate gas inlet passages leading from each gas supply pipe to the adjacent part of the combustion chamber, a plurality of separate pressure air inlet passages leading from each pressure air supply pipe to the adjacent regenerator chamber, by-pass connecting pipes between the main air supply pipe and the gas branch supply pipes, means to control the admission of by-pass air to the gas supply pipes in parallel or individually as desired, and means to reverse the direction of flow of the gas and air from one side of the furnace chamber to the opposite side.

7. A reversible regenerative gas fired furnace comprising in combination separate gas and pressure air inlets on each side of the furnace, a plurality of regenerator chambers below the furnace hearth arranged in pairs on each side of the longitudinal central line of the furnace, loosely packed or chequered fire bricks disposed in each regenerator chamber, a partition dividing each regenerator chamber into compartments, an air pressure inlet common to two of said compartments, branched passages leading from the common pressure air inlet and connecting the same with the compartments, means to supply and deliver pressure air to and through said compartments to the air inlets to the furnace and means to reverse the direction of flow of the gas and pressure air simultaneously.

8. A reversible regenerative gas fired furnace, comprising, in combination, a combustion chamber, a hearth, pressure air regenerator chambers formed entirely within the furnace structure below the hearth and divided into two parts, each having an opening communicating through the hearth with the combustion chamber, a gas supply pipe for coal gas exterior thereof, a pressure air supply pipe exterior thereof, a plurality of gas inlets connecting with the gas supply pipe and delivering gas to the combustion chamber on each side thereof, a plurality of separate pressure air inlet passages leading from the pressure air supply pipe to each of the regenerator chambers at the bottom thereof, and means to reverse the direction of flow of the gas and pressure air to the furnace.

9. A reversible regenerative gas fired

furnace, comprising, in combination, a combustion chamber, a hearth, pressure air regenerator chambers formed entirely within the furnace below the hearth and communicating by openings through the hearth with each side of the combustion chamber, a gas supply pipe for coal gas on each side of the furnace and exterior thereof, a pressure air supply pipe on each side of the furnace and exterior thereof, a plurality of separate gas inlets leading from each gas pipe to the combustion chambers on opposite sides of the furnace, a plurality of separate pressure air inlet passages leading from each pressure air pipe to the adjacent regenerator chamber below the hearth, and means to simultaneously reverse the direction of flow of gas and air from one side of the furnace chamber to the opposite side, whereby one of the regenerator chambers acts simultaneously and alternately to heat the incoming pressure air to the furnace while the other absorbs heat from the products of combustion passing therethrough to the stack.

10. In a reversible regenerative gas fired furnace, the combination of a combustion chamber, a hearth, a partition supporting the hearth and disposed centrally thereof, a regenerator chamber on each side of the hearth and in communication with the combustion chamber but out of communication with each other, means to deliver pressure air separately to said regenerator chambers, means to deliver coal gas to the combustion chamber, and means to effect reversal of the direction of the flow of the coal gas and pressure air from one side of the combustion chamber to the opposite side.

11. A reversible regenerative gas fired furnace comprising in combination a furnace structure, a hearth within said structure, pressure air regenerator chambers under said hearth and within the furnace structure, means to admit pressure air to each regenerator chamber, said means also acting to permit the escape of the products of combustion through said regenerator chamber, a gas supply pipe on each side of the furnace and exterior thereof, a plurality of separate gas inlet passages leading from each gas pipe to the adjacent part of the combustion chamber, a plurality of separate pressure air inlet passages leading from each pressure air pipe to the adjacent regenerator chamber, and means to reverse the direction of flow of gas and air from one side of the furnace combustion chamber to the opposite side.

In testimony whereof I have hereunto signed my name.

WALTER RATLEDGE TWIGG.
